UNITED STATES PATENT OFFICE

JOHN C. DUNN, OF PROVIDENCE, RHODE ISLAND

CLOTH BOARD AND METHOD OF ITS MANUFACTURE

Application filed February 3, 1927, Serial No. 165,721. Renewed April 29, 1929.

My invention relates to cloth boards and specifically relates to cloth reels, which are a type of cloth board having a frame having a covering therearound.

Up to the present time on all cloth reels manufactured, the manufacturer has always used paper to form an additional covering on the ends that are displayed. As these ends have been used to a certain extent for trade marks or to carry the name of the manufacturer of the material or for other purposes, it has been a source of constant dissatisfaction, due to the fact that in use this paper would dry out and thus leave wrinkles or blisters on the ends tending to obscure the indicia thereon and as the ends have been constantly handled every time a bolt of cloth is removed from the retailer's shelves it has only been a matter of a short time before the paper and covering has become torn and destroyed, thus causing destruction of the manufacturer's identification mark. Due to the fact that this paper covering has been worn, soiled and torn from constant handling, it has made the goods wound on the reel take on an inferior look, in many instances causing the retailer to rewind the goods and to place them on a fresh reel in order to keep his stock neat and fresh looking.

My invention comprises inserting on the ends of said boards or reels in place of the usual paper covering hitherto attached, rigid cap members preferably having the usual trade mark or other indicia thereon firmly secured to each end thereof. Among the advantages of inserting these rigid reinforcing cap members on the ends of the reels or cloth boards are the following. In order that the ends of each board or reel may receive the standard cap members they are made to a standard size within a few thousandths of an inch and when fitted into the reinforcing caps the ends of each board or reel are of an exact size. Formerly the ends of reels or boards would vary as much as one-eighth of an inch due to the warping of the different types of wood used and also due to the difficulty of evenly folding the usual white paper covering around the ends. As my invention provides ends of standard size they will always form a perfect fit in the cups of the machines for winding cloth thereon. The reinforcing preferably metallic cap members also bind the normal paper covering normally used on cloth boards to the frame of the reel at each end thereof. Whereas formerly manufacturers have depended on the craft paper alone sticking to the end mullion in order to keep the reel from breaking down when handled as my preferably metallic cap members fit over this craft paper covering as a force fit they act as a blocking device between the wood and cap to always firmly retain the paper or other covering on the reel. The rigid outer end of the rigid cap will not wrinkle or blister in use and will not become torn on handling. As a result of this, it is obvious that manufacturer's trade mark or other indicia may be stamped, lithographed or otherwise placed thereon, which will assure the manufacturer that so long as there is a yard of goods on this reel his advertising or trade mark will be in fit condition and readable. If desired there is plenty of room on the ends of the rigid cap member to lithograph distinctive pictures, designs or trade marks in different colors thereon. Whereas hitherto manufacturers of cloth reels have depended solely on the glue or nails to hold the end mullions in their proper places, which method of binding has not proved entirely satisfactory due to the fact that the glue under certain conditions is apt to break, and the nails being driven into the mullion lengthwise of the grain thus have no holding qualities, due to the construction of my rigid caps they not only bind the side rails to the end mullions, but also keep the end mullions from pushing in or turning over as they often have in the past. I preferably bead in or crimp preferably circumferentially the sides of each cap a distance from the end thereof. It is obvious that this circumferential crimp will aid in holding the paper covering to the reel and the end mullions in place between the rails, and assist in retaining the cap members to the ends of the reel.

These and such other objects of my invention as may hereinafter appear will be best understood from a description of the accom-

panying drawings which illustrate various embodiments thereof.

In the drawings, Fig. 1 is a side elevation showing one end of a cloth reel being pressed in a die, and in dotted lines said end before 5 pressing.

Fig. 2 is a side elevation showing a cap member about to be pressed on to a precompressed end of a reel.

10 Fig. 3 is a side elevation of an end of a reel having a cap member pressed thereon.

Fig. 4 is a side elevation of an end of a reel having a cap member secured thereon by means of a circumferential bead.

15 Fig. 5 is a perspective view of a cloth reel constructed in accordance with my invention.

In order that the construction of my improved cloth board may be best understood, I will first describe its method of manufacture. As stated my invention relates to cloth 20 boards whether they comprise a thick slab of wood or paper pulp formed up into the shape of a cloth board, or comprise a reel having a frame around which is wound the usual 25 covering. Where the board comprises an integral cellular slab it is also preferably covered with a paper or other covering. As stated hitherto, the ends of integral boards or frame reels have hitherto been covered 30 with an additional paper covering usually thicker white paper than the paper normally used as the covering of the board. While my invention is adapted for use on any type of cloth board, which term I use broadly to 35 include both integral cellular units or slabs and cloth reels as hitherto described it is particularly adapted for use on cloth reels for as stated it not only serves to furnish rigid ends for displaying trade marks thereon and firmly uniting the usual covering to 40 the frame or board, but also when employed on reels serves to keep them from slipping or warping. I therefore will describe my invention as applied to the usual type of a 45 cloth reel.

In the drawings Fig. 1 illustrates an end of a usual cloth reel, which comprises a frame 50 composed of the wooden side rails 12, end and cross mullions 14 suitably secured together either by glue or nails. 15 indicates the usual covering which is normally constructed out of flexible craft paper and which preferably is secured to said frame approximately throughout the length thereof to form 55 the body of said frame. It is obvious that a reel thus constructed as well as the usual pulp board or wooden slab has ends of inherently resilient material, the wood being inherently resilient as much as the pulp. While the cap 60 members 16 of my invention may be secured to said reel or board in any suitable fashion, I preferably uniformly compress the periphery of said board for a distance inwardly from the ends thereof as at 18 preferably by 65 forcing said ends 18 into a suitable die 20

having a smaller circumference than the normal circumference of said end, (Fig. 1). The upper portion of Fig. 2 illustrates the reel immediately after it is withdrawn from the die 20 having the compressed end 18. I 70 then immediately press the rigid reinforcing preferably metallic cap members 16, preferably constructed of thin steel or other metallic or rigid material, which have sides preferably of slightly smaller perimeter than those of 75 the precompressed ends of said reels on said compressed ends before said inherently resilient compressed ends 18 tend to inherently expand to their precompressed state. 80 It is obvious that after said caps 16 are inserted on said ends 18 as shown in Fig. 3 that they will be permanently retained on said ends, by the inherent tendency of said cellular ends to expand. As the sides 22 of 85 said caps normally taper outwardly, it is 85 obvious that they will form a substantially flush fit with the center portion of the periphery of said reel as shown in Fig. 3. While best results are attained by first precompressing the ends 18 as shown in Fig. 1, the caps 16 may be directly pressed on said ends without any precompressing. To further assist in retaining said caps to said ends, I preferably crimp in or form a bead 17, preferably 90 circumferential around said cap in any suitable manner as by a suitable crimping tool. The bead 17 bites into the wooden side rails 12 and end mullions 14 to assist in retaining 95 said cap members 16 to said reels, (Fig. 4), said covering 15 to the frame and the end mullions 14 in position. If desired the cap members may be secured to said reels by merely placing them over the uncompressed 100 ends of said reels and then suitably forming the bead 17 as shown in Fig. 4 or the cap members may be suitably secured to the ends 105 of the reel in any suitable fashion. I employ the words "crimping in the sides of the cap members" to cover any method of forcing the middle as shown, inner edge or any portion 110 of the sides thereof, circumferentially or otherwise inwardly so that they will bite into the cellular structure. As the inner ends of the cap members are substantially flush with the sides of the reel, there will be no metal 115 edge to catch and tear the fingers in handling the reels. It is obvious that I have provided a new type of cloth board or reel having rigid 120 ends which function to attain the novel objects and advantages hitherto described. Though I preferably affix a rigid cap member to each end of the board, and employ the plural in the claims, it is obvious that one 125 rigid cap member only may be inserted on one end thereof without departing from my invention.

130 It is understood that my invention is not limited to the specific embodiments shown and that various deviations may be made

therefrom without departing from the spirit and scope of the appended claims.

What I claim as new and desire to secure by Letters Patent is:

- 5 1. The herein described improved method of making cloth boards which comprises forming cloth boards having coverings secured thereto substantially throughout the length thereof and ends of inherently resilient cellular material, compressing the periphery of said boards for a distance inwardly from the ends thereof, then immediately pressing rigid reinforcing metallic cap members having sides of slightly smaller perimeter than that of the precompressed ends on said precompressed ends before said ends inherently expand, whereby said rigid caps may be permanently retained on said ends by the inherent tendency of said precompressed ends to expand and crimping in the sides of said cap members and closed portions of the cellular boards to assist in retaining said members to said boards.
- 20 2. The herein described improved method of making cloth boards, which comprises forming cloth boards having coverings secured thereto substantially throughout the length thereof and ends of inherently resilient cellular material, compressing the periphery of said boards for a distance inwardly from the ends thereof, then immediately pressing rigid cap members having sides of slightly smaller perimeter than that of the precompressed ends on said precompressed ends before said ends inherently expand, whereby said rigid caps may be permanently retained on said ends by the inherent tendency of said precompressed cellular ends to expand.
- 25 3. The herein described improved method of making cloth boards, which comprises forming cloth boards having coverings secured thereto substantially throughout the length thereof, pressing rigid cap members having sides on the ends thereof and crimping in the sides of said cap members and enclosed portions of the boards to assist in retaining said members to said boards.
- 40 4. A cloth board having a covering secured thereto approximately throughout the length thereof and rigid reinforcing cap members firmly encompassing each end thereof having integral unbroken sides binding said caps to said ends.
- 45 5. A cloth board having ends composed of inherently resilient cellular material and having a covering secured thereto substantially throughout the length thereof and rigid cap members pressed on each precompressed end thereof over said covering and retained thereon by the inherent tendency of said cellular ends to expand, the sides of said cap members being crimped into said cellular material to assist in retaining said members to said board.
- 50 6. A cloth board having ends composed of

inherently resilient cellular material and rigid cap members pressed on each end thereof, the sides of said cap members being crimped into said cellular material to assist in retaining said members to said board.

7. A cloth board having ends composed of inherently resilient cellular material and rigid cap members pressed on each end thereof of having integral unbroken sides binding said caps to said ends.

8. A cloth reel comprising a frame composed of wooden side rails, end and cross mullions secured together, a covering secured thereto substantially throughout the length thereof and rigid cap members pressed on each end thereof, the sides of said cap members being crimped into said rails and end mullions to assist in retaining said members to said reel.

9. A cloth reel comprising a frame composed of wooden side rails, end and cross mullions secured together, a covering secured thereto substantially throughout the length thereof and rigid cap members pressed on each end thereof having integral unbroken sides binding said caps to said ends.

10. A cloth reel comprising a frame composed of wooden side rails, end and cross mullions secured together and a covering secured thereto substantially throughout the length thereof and rigid cap members firmly encompassing each end thereof having integral unbroken sides binding said caps to said ends.

In testimony whereof I affix my signature.
